FISH LURE

George C. Stauffer, Altoona, Pa.

Application September 5, 1950, Serial No. 12,055

Term of patent 3½ years

(Cl. D31—4)

To all whom it may concern:

Be it known that I, George C. Stauffer, a citizen of the United States, residing at Altoona, in the county of Blair and State of Pennsylvania, have invented a new, original, and ornamental Design for a Fish Lure, of which the following is a specification, reference being had to the accompanying drawing, forming part thereof.

Figure 1 is a perspective view of a fish lure, showing my new design;

Figure 2 is a side elevational view;

Figure 3 is a top plan view thereof; and

Figure 4 is a front elevational view of the same.

I claim:

The ornamental design for a fish lure, as shown.

GEORGE C. STAUFFER.
